FILLING FORK WELL CLEANER

Howard W. Carroll, Rock Hill, S. C.

Application July 27, 1950, Serial No. 176,130

8 Claims. (Cl. 139—379)

1

This invention relates to looms and more especially to a filling fork well cleaner therefor.

The lay associated with most types of looms is usually provided with a transverse groove or filling fork well intermediate the ends thereof in which a filling fork moves upon each beat-up stroke of the lay, the function of this filling fork being to effect operation of a conventional stop motion of the loom for stopping the loom in the event a filling yarn is not thrown across the lay. In order to insure efficient operation of the filling fork, it has been necessary to periodically stop the loom and remove accumulations of lint or other foreign matter from the filling fork well.

It is, therefore, an object of this invention to provide means for automatically cleaning the filling fork well during continuous operation of the loom.

It is another object of this invention to provide an improved filling fork well cleaner comprising a tubular member which extends past the filling fork well at the rear of the lay or adjacent the reed associated with the lay of a loom, and this tubular member having a plurality of openings therein and to provide means connected to the tubular member automatically operable upon each beat-up stroke of the lay for introducing a blast of air to the tubular member to be exhausted through said openings in the tubular member to thus dislodge or blow away any accumulations of lint adjacent and in the filling fork well.

It is another object of this invention to provide, in an apparatus of the type described, means for introducing blasts of air to the tubular member upon each beat-up stroke of the lay comprising a cylinder suitably secured to the lay and having the tubular member communicating with one end thereof and which has a spring loaded plunger or piston rod mounted in the other end thereof normally biased to extend out of the cylinder and to the inner end of which a piston is connected. The outer end of the piston rod will, upon each beat-up stroke of the lay, engage the breast beam, or any other suitable fixed projection on the loom, for imparting inward movement to the piston rod and its associated piston to thus compress air within the cylinder and to force the compressed air through the tubular member.

It is still another object of this invention to provide, in an apparatus of the type described, an extension on said tubular member which extends forwardly in parallel relation to the filling fork well and penetrates the lay with the free

2

end of the forwardly extending projection being open for emitting a blast of air upon each beat-up stroke of the lay forwardly of the lay against suitable cam means secured on the lay for imparting movement to the filling fork so that the blast of air emitted from the free end of the tubular projection will remove accumulations of lint from the cam means to insure efficient operation of the filling fork.

10 Some of the objects of the invention having been stated, other objects will appear as the description proceeds when taken in connection with the accompanying drawings in which—

15 Figure 1 is a fragmentary top plan view showing a portion of one side and the front of a loom and showing the lay thereof with the improved filling fork well cleaner associated therewith;

20 Figure 2 is an enlarged vertical sectional view taken substantially along the line 2—2 in Figure 1 and showing the improved filling fork well cleaner associated with the breast beam and lay of the loom;

25 Figure 3 is an enlarged vertical sectional view through the lay of the loom and showing a part 25 of the conventional actuating means for the filling fork being taken substantially along the line 3—3 in Figure 1;

30 Figure 4 is a fragmentary elevation, with parts in section, looking substantially along the line 4—4 in Figure 1 and showing a part of the conventional mechanism associated with the lay of the loom for effecting operation of the filling fork in timed relation to movement of the lay;

35 Figure 5 is a fragmentary elevation with parts in section looking substantially along the line 5—5 in Figure 3 and showing the conventional cam means for effecting operation of the filling fork;

40 Figure 6 is an enlarged fragmentary elevation looking substantially along the line 6—6 in Figure 4;

45 Figure 7 is an enlarged vertical sectional view, through the cylinder for directing compressed air to the filling fork well but showing the same disassociated from the loom for purposes of clarity and is taken substantially along the line 7—7 in Figure 1;

Figure 8 is a schematic fragmentary view showing a part of the air directing means and taken substantially along the line 8—8 in Figure 3;

Figure 9 is an enlarged fragmentary top plan view similar to the central portion of Figure 1 but showing a modified form of the invention associated therewith;

55 Figure 10 is an enlarged vertical sectional view

similar to Figure 2 and is taken substantially along the line 10—10 in Figure 9.

Referring more specifically to the drawings, the numeral 10 indicates one of the side frame members of a loom, the upper front end of which is secured, in a conventional manner, to a conventional breast beam 11. The loom side frame member 10 also supports a conventional bearing block 12 suitably secured thereto as by screws 13 and in which one end of a crank shaft 14 is mounted for rotation. Only a part of the crank shaft 14 is shown and this crank shaft is driven in a well known manner and is provided with cranks 15, only one of which is shown in Figure 1. The crank 15 has the rear end of a pitman rod 16 rotatably mounted thereon, the front end of the pitman rod 16 being oscillatably connected as at 17 to a sword 20. The lower end of the sword 20 (Figure 4) is fixedly mounted on a conventional rocker shaft 21 which is mounted for oscillation in the loom side frame member 10 and in a similar loom side frame member not shown disposed at the other side of the loom.

A sword, not shown, similar to the sword 20 is disposed adjacent the right-hand side frame member which is not shown in the drawings and the swords 20 suitably support a conventional lay 22, this lay 22 having conventional shuttle boxes broadly designated at 23 on opposed ends thereof, only one of which is shown in Figure 1 for reception of shuttles indicated at 24a. The shuttle box 23 includes a conventional shuttle box bottom plate 24, the upper surface of which is disposed in substantially the same plane as a race plate or shuttle race 25, the shuttle race 25 being suitably covered with a fabric material 26 (Figure 2).

There are many types of lays with which the present invention may be used and the particular type of lay shown in the drawings is shown by way of illustration only, it being understood that the present invention may be used with any type of lay. The particular lay shown in the drawings is of the type such as is usually employed in association with looms of the XL and XD types manufactured by the Draper Corporation of Hopedale, Massachusetts.

A conventional reenforcing angle bar 30 is secured in a conventional manner to the lower surface of the lay 22 and extends substantially the full length of the lay usually terminating at opposed ends thereof short of the shuttle boxes 23, only one of which is shown in Figure 1. The lay 22 is provided with a groove extending substantially the entire length thereof between the shuttle boxes 23 for reception of a loose reed holder 31 which is held in spaced relation to the rear surface of the lay 22 by conventional spacing or adjustment bolts not shown and which is held against the spacing bolts by conventional loose reed clamp hooks 32, there being a plurality of reed clamp hooks 32 spaced along the lay 22. The reed clamp hooks 32 slidably penetrate the lay 22 and are surrounded by suitable compression springs 33 which bear against nuts 34 on the reed clamp hooks 32 at their front ends, the rear ends of the reed clamp hooks 32 bear against the front surface of the lay 22 to thus normally urge the loose reed against the conventional spacing means provided therefor, not shown, between the front surface of the loose reed holder 31 and the rear surface of the lay 22. Thus, a groove 35 is formed between the rear surface of the lay 22 and the front surface of the loose reed holder 31.

It will be observed in Figures 1 and 2 that the loose reed holder 31 supports the lower edge of a

conventional reed 36 and the loose reed holder 31 also supports a conventional glass rod 37 which is adapted to prevent warp yarns Y from engaging the rear upper edge of the loose reed holder 31. Since most loose reed holders, such as the holder 31 are made of wood or other light material, the loose reed holder 31 is supported or cradled in a reenforcing loose reed angle iron 40. The warp yarns Y are formed into fabric F upon each beat-up stroke of the lay 22 in a conventional manner and the fabric F passes over a pair of cloth guide rods 41 and 42 suitably supported by the breast beam 11 after which the cloth or fabric F extends downwardly to a suitable cloth take-up mechanism, not shown.

The lay 22, the race plate 25 and the fabric 26 are cut away to form a filling fork well 45 which extends transversely of the lay 22 and intermediate the ends thereof and in which a conventional filling fork 46 is adapted to fall or to be moved upon the absence of a filling yarn being thrown across the lay to be beat-up by the reed 36 upon a subsequent beat-up stroke.

The prongs of the filling fork 46 are suitably secured at their front ends on a conventional filling fork prong holder 47 oscillatably mounted in a center fork bracket 50. The filling fork holder 47 has a substantially L-shaped extension 51 extending through one side of the filling fork bracket and which is normally urged downwardly against the upper surface of a filling fork cam 52 by a torsion spring 53. The filling fork cam 52 is fixedly mounted on a reciprocating center fork knock-off rod 54 which is mounted for reciprocation in the bracket 50 as well as a guide block 55 suitably secured to the front surface of the lay 22. The left-hand end of the knock-off rod 54 in Figure 1 is pivotally connected as at 56 (Figure 6) to a center fork knock-off lever or bell crank 57. The knock-off lever or bell crank 57 is oscillatably mounted as at 60 on a knock-off bracket 61 suitably secured, as by screws 62 to the front surface of the lay 22.

The center fork knock-off bracket 61 has a pair of vertically spaced projections 63 thereon in which a fork knock-off actuating rod 64 has vertical sliding movement. This fork knock-off actuating rod 64 has a bunter sleeve or bunter 65 fixedly mounted thereon, as by a screw 66, and which is adapted to engage an arm 67 projecting from the bell crank 57 upon each upward stroke thereof. Vertical movement is imparted to the bunter 65 upon each backward stroke of the lay 22 by a link or push rod 70 (Figure 4) which is pivotally connected, as at 71, at its upper end to the bunter 65 and is pivotally connected, as at 72, at its lower end to a bracket 73 suitably secured, as by screws 74 to the inner surface of the loom side frame member 10.

The center fork knock-off lever 57 has a forwardly projecting knock-off bar 75 integral therewith which is adapted to move between forwardly projecting stops 76 and 77 which are spaced apart from each other and are integral with the bracket 61.

Referring again to Figures 1 and 5, it will be observed that the right-hand portion of the center fork knock-off rod 54 is surrounded by a compression spring 80, the left-hand end of which bears against the bracket 50 and the right-hand end of which bears against a collar 81 suitably secured on the knock-off rod 54 and thus the compression spring 80 normally urges the knock-off rod 54 from left to right in Figures 1, 5 and 6.

and thus normally urges the projection 75 of the lever 57 against the stop 71.

Now, upon each backward stroke of the lay 22, the bunter 65 is moved upwardly due to the reduced distance between the bracket 61 and the bracket 73 (Figures 4 and 6) and thus the bunter 65 will engage the arm 67 of the lever 57 causing the projection 75 to move into engagement with the stop 76 projecting from the bracket 61. This will cause the cam 52 to move from right to left in Figures 1 and 5 during backward movement of the lay 22 thus causing the prongs of the filling fork 46 to move upwardly at their rear ends or toward the observer in Figure 1. The shuttle 24a is then thrown across the lay 22 and, in the event a filling yarn is not thrown across the lay, upon the following beat-up stroke of the lay 22, the torsion spring 53 will cause the prongs of the filling fork 46 to move into the filling fork well 45 below the level of the fabric material 26 or the top surface of the shuttle race plate 25.

Thus, as the lay 22 moves forwardly, in which event the bunter 65 moves downwardly and out of engagement with the arm 67 (Figure 6) of the lever 57, the extension 51 of the filling fork 46 will move into the notch 52a (Figure 5) as shown in Figure 5 thus limiting movement of the cam 52, the knock-off rod 54 and the projection 75 on the knock-off lever 57 to cause the projection 75 to stop in a position intermediate the projections 76 and 77 on the knock-off bracket 61. This will position the projection 75 to where it will actuate conventional knock-off mechanism, not shown, for stopping the loom.

On the other hand, when a filling yarn is thrown across the lay by the shuttle 24a the filling yarn will extend across the filling fork well 45 and the tension in the torsion spring 53 is such that it will not force the prongs of the filling fork 46 downwardly into the filling fork well 45 as the prongs engage the filling yarn. Thus, the extension 51 of the filling fork 46 will remain in a partially elevated position sufficiently high enough so that the cam 52 may continue its movement from left to right upon a forward stroke of the lay 22 without the projection 51 of the filling fork 46 engaging the notch 52a and, therefore, the compression spring 80 will urge the projection 75 of the knock-off lever 57 to the position shown in Figure 6, that is, against the projection 77 on the knock-off bracket 61. With the projection 75 of the knock-off lever 57 in the position shown in Figure 6, the projection 75 will not engage the conventional knock-off stop motion of the loom and will thus permit the loom to continue its operation.

The parts of the loom heretofore described are conventional and constitute no part of the present invention, however, it is with these parts that the present invention is adapted to be associated. The particular stop motion heretofore referred to and which is adapted to be actuated by the positioning of the projection 75 (Figure 6) on the knock-off lever 57 upon the projection 75 being positioned intermediate the projections 76 and 77 is of the type such as is associated with looms of the type heretofore described and this particular stop motion is clearly shown on a sheet entitled "Center Fork Filling Motion," Sheet No. 4, copyrighted 1939 by Draper Corporation, Hopedale, Massachusetts, this sheet being a part of a catalogue of parts distributed by said Draper Corporation.

Heretofore during continuous operation of the loom a considerable amount of lint and other

fine matter would accumulate in the filling fork well 45 and the notch 52a of the filling fork cam 52. This would result in failure of the prongs of the filling fork 46 to move into the filling fork well 45 due to the fact that the accumulation of the lint in the filling fork well would restrict movement of the prongs of the filling fork 46 into the filling fork well 45 in the event a weft or filling yarn is not thrown across the lay or the accumulation of lint in the notch 52a would restrict movement of the extension 51 of the filling fork 46 into said notch and, therefore, the loom would continue to operate although a filling or a weft yarn may not have been thrown across the lay and this would result in imperfect fabric being woven. Heretofore, in order to avoid an excessive accumulation of lint in the filling fork well 45 or the notch 52a of the knock-off cam 52, it has been necessary for the operator to stop the loom periodically and to manually remove the lint or other foreign matter from the filling fork well 45 and the notch 52a of the cam 52. This invention provides means for preventing an accumulation of lint in either the notch 52a of the cam 52 or the filling fork well 45.

The filling fork well cleaner comprises a cylinder 90 (Figures 1, 2 and 7) which may be of any desired construction and is shown as being closed at its right-hand end in Figure 7 as at 91. The left-hand end of the cylinder 90 is closed by a cylinder head member 92 threadably mounted on the cylinder 90 and in which a piston rod or plunger 93 has longitudinal sliding movement. The piston rod has a piston in the form of cup washer 94 mounted on the right-hand end thereof and this cup washer being loosely mounted on the piston rod 93 and held in place by washers 95 engaging opposed surfaces of the cup washer 94 and spaced nuts 96 are threadably mounted on the piston rod 93 and engage the remote surfaces of the respective washers 95 to thus secure the cup washer 94 on the right-hand end of the piston rod 93.

The cylinder head 92 has an annular projection 97 integral therewith which surrounds the piston rod 93 and which is surrounded by one end of a coiled compression spring 100. The compression spring, of course, surrounds the exposed portion of the piston rod 93 and its left-hand end in Figure 7 is mounted on a pilot sleeve 101 slidably mounted on the piston rod 93. A pair of lock nuts 102 and 103 are mounted on the outer or free end of the piston rod 93 and the pilot sleeve 101 is urged against the lock nut 103 by the compression spring 101 to thus normally urge the piston 94 from right to left in Figure 7.

In order to prevent an accumulation of lint or other foreign matter between the coils of the compression spring 100, a cleaner sleeve 105 is loosely mounted on the piston rod 93 between the projection 97 on the cylinder 92 and the pilot sleeve 101 and, upon movement of the piston rod 93 relative movement is caused between the cleaner sleeve 105 and the piston rod 93. The cylinder 90 has a port 106 therein adjacent the cylinder head 92 which is provided to permit ingress and egress of air between the piston 94 and the cylinder head 92 upon movement of the piston 93 longitudinally of the cylinder 90.

The cylinder 90 has a pair of oppositely directed radially extending projections or flanges 110 integral therewith which are penetrated by screws 111 serving as a suitable means for secu-

ing the cylinder 90 to the front surface of the lay 22, the lay 22 having a suitable cavity therein for reception of the rear portion of the cylinder 90 as is clearly shown in Figures 1 and 2. A tubular member or pipe 112 is suitably connected in communicating relation with the closed end 91 of the cylinder 90 as by a pipe elbow 113 which threadably penetrates the closed end 91 of the cylinder 90.

It will be observed in Figures 1 and 2 that the pipe 112 extends at substantially right angles to the axis of the cylinder 90 and extends along the groove 35 between the lay 22 and the loose reed holder 31. The loose reed holder has a notch or groove 114 therein which is provided for reception of a substantially U-shaped rearwardly bent portion 115 of the pipe 112 and which is disposed beneath the lower edge of the reed 36 as is clearly shown in Figure 2. The front surface of this rearwardly bent substantially U-shaped portion 115 is provided with a plurality of openings 116 (Figure 8) disposed in alignment with the filling fork well 45 for purposes to be presently described. The tubular member or pipe 112 then again extends along the groove 35, as at 117 (Figure 1) and has a forwardly extending portion 120 integral therewith which slidably penetrates the lay 22 and the free end of which terminates closely adjacent the notch 52a in the cam 52 as will be observed in Figure 3.

The piston rod 93 is of such length that in the course of beat-up stroke of the lay 22, the free or outer end thereof will engage the breast beam 11 substantially as shown in Figure 2 and with continued forward movement of the lay 22 to its beat-up point, the piston rod 93 will then recede into the cylinder 90 causing relative movement of the piston or cup washer 94. This will, of course, cause compressed air to be forced from the cylinder 90 through the pipe elbow 113 and the pipe 112 to be discharged through the openings 116 in the substantially U-shaped portion of the tube or pipe 112 and as well as through the free outer end of the forwardly projection portion 120. It is thus seen that upon each beat-up stroke of the lay 22, a blast of air will be emitted from the openings 116 in the U-shaped portion 115 of the pipe 112 and through the free end of the forwardly projection portion 120 of the pipe 112 to thus remove and prevent the accumulation of lint or other foreign matter in the filling fork well 45 as well as in the notch 52a of the cam 52.

It is evident, that upon each backward stroke of the lay 22 the compression spring 100 (Figure 7) will urge the piston rod 93 outwardly with respect to the cylinder 90 and will cause the piston 94 to move from right to left thus positioning the piston rod for a repeat operation.

It is thus seen that there is provided an apparatus for cleaning the filling fork wells 45 and the notch 52a of the cam 52 upon each beat-up stroke of the lay 22 to thus insure efficient operation of the prongs of the filling fork 46 as well as insuring that the notch 52a of the cam 52 may be free of any obstructions which may prevent the extension 51 of the filling fork 46 from moving into said notch in the event a weft or filling yarn is not thrown across the lay.

Modified form

Referring to Figures 9 and 10 there is shown a modified form of the filling fork well cleaner which operates in substantially the same manner

as the original form of filling fork well cleaner shown in Figures 1 to 7, inclusive, and the same reference characters shall apply to those parts of the loom and the modified form of the invention shown in Figures 9 and 10 which are identical to the parts shown in Figures 1 to 8, inclusive, with the prime notation added to those parts shown in Figures 9 and 10.

The object of the modified form of the invention is primarily to provide means for mounting the cylinder which admits compressed air to the filling fork well 45' and the cam 52' without the necessity of providing a cavity in the lay 22' to avoid any possibility that the cavity may, in time, weaken the lay 22' structurally.

The modified form of filling fork well cleaner comprises a cylinder 125 which is substantially the same as the cylinder 90 shown in Figure 7. The cylinder 125 is closed at its right-hand end in Figure 9 by a cylinder head 126 in which a piston rod or plunger 127 has longitudinal sliding movement, there being a suitable piston 130 suitably secured on the inner end of the plunger 127 within the cylinder 125. The piston 130 may be identical to the piston comprising a cup washer 94 in Figure 7.

The cylinder 125 is provided with a projection or plate portion 131 which is penetrated by screws 132, only one of which is shown in Figure 10, for securing the cylinder 125 to the lower surface of the horizontal leg of the angle bar 30'.

It is evident that the particular type of structure shown in Figures 9 and 10 relating to the modified form of the filling fork well cleaner may be more readily adapted to the type of lay which does not have a separate loose reed holder and wherein the reed holder is an integral part of the lay. However, for purposes of clarity, the modified form of the invention is shown in association with the lay identical to that associated with the original form of the invention.

The plunger or piston rod 127 extends outwardly and rearwardly from the cylinder 125 and is then bent upwardly as at 134 and is bent at right angles to form a forwardly extending portion 135. This forwardly extending portion 135 slidably penetrates the vertical portion of the loose reed angle iron 40', the loose reed holder 31' and the lay 22'. The lay 22' is shown in Figures 9 and 10 as being substantially midway of its stroke in either direction and it will be observed that the forwardly extending portion 135 of the plunger 127 extends substantially beyond the front surface of the lay 22' and at the particular position at which the lay is shown in Figure 10, the free or front end of the portion 135 of the plunger 127 is shown in engagement with the rear surface of the breast beam 11'.

A compression spring 136 surrounds the forwardly projecting portion 135 of the plunger 127 and its right-hand end in Figure 10 bears against the front surface of the lay 22', its left-hand end bearing against a washer 137 which is held in adjusted position by lock nuts 138 and 139 threadably mounted on the left-hand end of the portion 135 of the plunger 127 in Figure 10.

A tubular member of pipe 112' which is substantially the same as the pipe 112 associated with the original form of the invention is provided in association with the modified form of filling fork well cleaner. The pipe 112' extends along the groove 35' between the lay 22' and the loose reed holder 31' and its left hand portion in Figure 9 is provided with a substantially U-shaped portion 115' which is provided with per-

forations or openings in the front surface thereof identical to the openings 116 associated with the pipe 112 and shown in Figure 8. The left-hand portion of the pipe 112' then extends along the groove 35' as at 117' and is bent to form a forwardly extending portion 120' the free end of which is open to permit compressed air to be emitted from the free end thereof as well as through the openings in the portion 115'. The pipe 112' differs from the pipe 112 only in the manner in which it is formed so as to communicate with the left-hand end of the cylinder 125 in Figure 10.

The right-hand end of the tube 112' or the end nearest the observer in Figure 10 is bent downwardly, as at 143 and is then bent rearwardly at the lower end of the portion 143 to form a horizontal portion 144, the pipe then being bent inwardly or to the left in Figure 9 to form a portion 145, the left-hand end of which is connected in communicating relation to the cylinder 125 adjacent the cylinder head 126 as at 146.

It is thus seen that the horizontal or forwardly extending portion 135 of the plunger 127 will cause a blast of air to be emitted from the openings in the portion 115' of the pipe 112' as well as from the free end of the forwardly projecting portion 120' of the pipe 112' upon each beat-up stroke of the lay 22' in substantially the same manner in which the operation is performed with respect to the original form of filling fork well cleaner shown in Figures 1 to 8, inclusive. It is evident that the compression spring 136 will cause the plunger 127 to recede into the cylinder 125 following each beat-up operation and during the return or backward stroke of the lay 22'.

In the drawings and specification there has been set forth a preferred embodiment of the invention and although specific terms are employed, they are used in a generic and descriptive sense only and not for purposes of limitation, the scope of the invention being defined in the claims.

I claim:

1. In a loom having a lay provided with a filling fork well intermediate the ends thereof and in which a filling fork is adapted to move when a weft yarn is not thrown across the lay, means for preventing the accumulation of lint and the like in the filling fork well comprising a pipe extending past the filling fork well and having at least one opening therein disposed in closely spaced relation to the filling fork well and means for directing compressed air through the pipe to be emitted into the filling fork well upon each beat-up stroke of the lay to remove and prevent accumulation of lint in said well.

2. In a loom having an oscillatable lay provided with a filling fork well therein, means for preventing an accumulation of lint and other foreign matter in said filling fork well comprising a pipe extending past said well in close proximity thereto, said pipe having at least one opening therein on its side adjacent the filling fork well and means for automatically admitting a blast of compressed air to said pipe to be emitted from said opening in the pipe upon each beat-up stroke of the lay.

3. In a loom having a lay provided with a filling fork well intermediate the ends thereof, means for automatically cleaning the filling fork well comprising an air cylinder mounted in fixed relation to the lay and having a piston therein, means for transmitting air from the air cylinder to the

filling fork well and means for actuating said piston upon each beat-up stroke of the loom.

4. In a loom having a lay, means for automatically cleaning said lay comprising an air cylinder mounted on said lay and having a piston therein, means for transmitting air from the air cylinder to a selected portion of the lay of the loom and means for actuating said piston upon each beat-up stroke of the loom.

5. In a loom having an oscillatable lay and also having a frame and said lay having a transverse groove in the upper surface thereof, apparatus for removing and for preventing an accumulation of lint and the like in said groove comprising a tubular member extending adjacent said groove and being provided with at least one opening therein facing said groove, a cylinder mounted in fixed relation to said lay, a piston mounted for longitudinal movement in said cylinder and having a piston rod integral therewith and projecting forwardly from said cylinder, spring means associated with said piston rod for normally urging the piston outwardly of said cylinder, means connecting said tubular member to the end of said cylinder remote from the end from which the piston rod projects, said piston rod being so positioned as to engage a portion of said frame upon each beat-up stroke of the lay whereby movement of the lay will cause the piston rod to move inwardly in said cylinder to cause a blast of air to be emitted from the opening in said tubular member adjacent the groove in the lay.

6. In a loom having a lay provided with a transversely extending filling fork well and also having a filling fork adapted to move into said filling fork well upon a beat-up stroke of the lay in the event a filling or weft yarn is not disposed across the filling fork well and also having a filling

35 fork knock-off cam and means on the filling fork for engaging said filling fork knock-off cam for transmitting oscillation to said filling fork, apparatus for removing and preventing accumulation of lint in the filling fork well and on said filling fork knock-off cam comprising a cylinder mounted in fixed relation to said lay, a plunger mounted for sliding movement in said cylinder and extending outwardly therefrom, a piston mounted on the inner end of said plunger relative to the cylinder, a pipe connected to one end

45 of said cylinder and extending past said filling fork well and also having an open end terminating closely adjacent the filling fork knock-off cam, said pipe being provided with at least one opening adjacent said filling fork well and

50 means on the loom engageable by the plunger upon each beat-up stroke of the lay to thus cause the plunger to move said piston longitudinally of the cylinder to, in turn, cause a blast of air to be emitted from the opening in the pipe adjacent the filling fork well as well as from the open end of said pipe to thus direct a blast of air into the filling fork well and onto the filling fork knock-off cam.

55 7. In a loom having a frame and also having a lay provided with a transverse filling fork well therein, means for preventing an accumulation of lint in said filling fork well comprising a cylinder, means securing the cylinder to the lower

60 surface of the lay, a plunger projecting outwardly from said cylinder and then upwardly and then horizontally and slidably penetrating said lay, spring means normally urging the plunger in one direction, a pipe connected to one end of said cylinder and extending adjacent said filling fork

well and having at least one opening therein, a piston on the end of said plunger disposed within the cylinder and means on the loom engageable by said plunger upon each beat-up stroke of the loom to cause movement of the piston in the cylinder to thus direct a blast of air from the opening in the pipe into the filling fork well for removing lint therefrom, said spring means serving to return the plunger to its original position following each beat-up stroke of the lay.

8. In a loom having a lay provided with a transversely extending filling fork well and also having a filling fork adapted to move into said filling fork well upon a beat-up stroke of the lay when a filling or weft yarn is not disposed across the filling fork well and also having a filling fork knock-off cam having means for engaging said filling fork for transmitting oscillation to said filling fork, apparatus for removing and preventing accumulation of lint in the filling fork well and on said filling fork knock-off cam comprising a cylinder mounted in fixed relation to said lay, a plunger mounted for sliding movement in said cylinder and extending outwardly therefrom and then vertically and then horizontally and 25 slidably penetrating the lay, a piston mounted on

the end of said plunger within the cylinder, a pipe connected to said cylinder and extending past said filling fork well and also having an open end terminating closely adjacent the filling fork knock-off cam, said pipe being provided with at least one opening adjacent said filling fork well and means on the loom engageable by the plunger upon each beat-up stroke of the lay to thus cause the plunger to move said piston longitudinally of the cylinder to, in turn, cause a blast of air to be emitted from the opening in the pipe adjacent the filling fork well and from the free end of said pipe to thus direct a blast of air into the filling fork well and onto the filling fork knock-off cam.

HOWARD W. CARROLL.
